UNITED STATES PATENT OFFICE.

GUSTAVE F. W. WOHLER, OF ST. PAUL, MINNESOTA.

DESIGN FOR AN AUTOMOBILE ORNAMENT.

Application filed June 29, 1927. Serial No. 22,604. Term of patent 14 years.

To all whom it may concern:

Be it known that I, GUSTAVE F. W. WOHLER, a citizen of United States of America, residing in St. Paul, county of Ramsey, State of Minnesota, have invented a new, original, and ornamental Design for an Automobile Ornament, of which the following is a specification, reference being had to the accompanying drawing which shows a perspective view of the ornament.

I claim:

The ornamental design for an automobile ornament, as shown.

GUSTAVE F. W. WOHLER.
